UNITED STATES PATENT OFFICE.

MALCOLM HARD, OF FLUSHING, NEW YORK, ASSIGNOR TO THE SUPERHEATER COMPANY, OF NEW YORK, N. Y.

INJECTOR.

Application filed April 2, 1926. Serial No. 99,288.

My invention relates to injectors and is specifically intended as an improvement upon that type of injector operated by either exhaust or live steam, an example of which is disclosed in U. S. Letters Patent No. 1,342,128, issued June 1, 1920 to J., J. C., and R. D. Metcalfe, although it is to be understood that the invention is not limited in its application to injectors of this type but may be applied to other forms of exhaust or live steam injectors as well.

In injectors of the type above referred to, the water regulation is ordinarily accomplished by moving the steam nozzle with respect to the water nozzle or cone in such manner as to vary the size of the opening between the water chamber of the injector and the water cone. Because of the comparative loose fit of the movable steam nozzle necessary in order to assure its freedom from binding under all operating conditions, the efficiency of the injector in prior forms of construction has been considerably reduced. In order to operate at the maximum efficiency, the steam nozzle must be exactly centered and in alignment with the water cone and with the loose fitting nozzle heretofore required, this accurate alignment cannot be maintained. Furthermore, the prior form of comparatively loosely fitted nozzle permits the leakage of some steam from the steam chamber of the injector past the nozzle into the water chamber, with a consequent heating effect on the water in the water chamber, resulting in a lowered efficiency of the injector because of the higher water temperature at the point where the water and steam combine.

In order to minimize this latter objection, prior forms of nozzles have been provided with packing to prevent leakage, but this remedy is not wholly effective and the packing is in itself objectionable in the injector.

The general object of the present invention is, therefore, the provision of an improved form of steam nozzle construction which will eliminate the objections above referred to. Other and more detailed objects of the invention will appear in connection with the following detailed description of a preferred form of the invention.

I have illustrated the invention as applied to an exhaust steam injector of the type disclosed in the U. S. patent above referred to, but it is to be understood that the invention

is applicable to any injector of the type wherein a movable steam nozzle is employed. In the drawing, Fig. 1 is a longitudinal vertical section taken through such an injector, Fig. 2 is a fragmentary portion of Fig. 1 reproduced on a larger scale and showing half sections of the steam nozzle in two positions, and Fig. 3 is a fragmentary section showing the prior form of nozzle construction, over which the present invention is an improvement.

Referring now to Fig. 1, the injector housing 1 is shown as comprising a number of sections, but it will be readily understood that the housing of the entire injector may be integral and is sectioned merely for convenience in assembling and aligning the several nozzles. The exhaust steam for operating the injector enters through the inlet 2 controlled by the fluid pressure actuated valve 3. Supplemental high pressure steam is admitted to the injector through a suitably controlled passage 4 and nozzle 5. Auxiliary live steam at low pressure is supplied to the injector, at times when exhaust steam is not available, through the passage 6, from which it enters the steam chamber 7 by way of suitable ports 8. Water is supplied through inlet 9 to the water chamber 10, from which it passes to the water cone 11. Steam, either exhaust or auxiliary, as the case may be, when supplied from the chamber 7 to the main low pressure steam nozzle 12, and after combining with the water supplied through the water cone 11, passes through the secondary steam nozzle 13 and combining tube 14 to the delivery tube 15 and from the injector by way of check valve 16 and outlet 17. The form of injector just described forms no part of the present invention and need not be described in further detail.

In order to make clear the nature of the present improvement over prior forms, the form of exhaust steam nozzle heretofore used in this type of injector has been illustrated in Fig. 3. In this form of construction the injector housing forms a cylindrical passageway connecting the steam chamber 7' with the water chamber 10', and in which is slidably mounted a steam nozzle 12'. The nozzle 12' extends through the water chamber 10' to enter the water cone 11', and is provided with packing 18 to prevent steam leakage from the steam cham-

ber into the water chamber. The housing 1' is provided with an opening to receive a rotating control member 19', which passes through a suitable stuffing box 20' and carries at its lower end an eccentric pin 21', engaging a suitable recess 22' in the nozzle 12'. As will be readily apparent, the rotation of the control member 19' by means of a suitable handle will cause longitudinal movement of the nozzle 12' and a consequent regulation of the opening from the water chamber 10' into the water cone 11'.

According to my present invention, the steam and water chambers, water cone and steam nozzle may be in the same relative position as in the prior forms of construction, but the steam nozzle is separated from the water chamber by an annular web extending through the water chamber and surrounding the steam nozzle. In the preferred form, which I have illustrated in detail in Fig. 2, a cylindrical passage is formed by the injector housing between the steam chamber 7 and water chamber 10. An annular bushing, or sleeve, 23 is mounted in said passage preferably by means of a tight press fit, the inner surface of the cylindrical portion of the sleeve forming a bearing for the reception of the steam nozzle 12. Nozzle 12 is mounted in sleeve 23 with a comparatively loose sliding fit to allow for all possible expansion without binding. For the purpose of illustration, I have shown the nozzle in Fig. 2 as longitudinally split, the upper half 33 of the nozzle being shown in one extreme position and the lower half of the nozzle being shown in the opposite extreme position. The sleeve 23 is provided with a conical extension, or web, extending through the water chamber into the water cone, and at the outer end of the web the inner surface thereof is formed to provide a cylindrical bearing surface. The nozzle 12 is tapered in the usual manner, but at the small, or delivery, end of the nozzle, the outer surface is made cylindrical in form and engages the bearing formed in the outer end of the extended web of sleeve 23.

While I have shown the bearing-forming web extending across the water chamber as comprising a part of the bushing, or sleeve, 23, it will be readily apparent that this web may, if desired, be formed as an integral portion of the housing casting. In order, however, to simplify the housing casting and to perform the necessary machining more advantageously, I prefer to make the web as shown, as a portion of the sleeve 23.

The sleeve 23 is provided with an opening 60 registering with a corresponding opening in the injector housing, which receives the actuating member 19, passing through the stuffing box 20 and having mounted thereon the eccentric pin 21 extending into a suitable recess 22 in the nozzle 12.

With the steam nozzle constructed in accordance with my invention, a clearance in the sliding fit between the nozzle and sleeve 23 of from .008" to .010" may be employed, as the second bearing formed by the extended web serves to center and guide the outlet end of the nozzle in the water cone. Because of the smaller dimensions of these parts, the clearance in this latter bearing may be made smaller than in the larger bearing, .002" or .003" being sufficient. It will be readily apparent from an inspection of Fig. 3 that in the prior form of construction, any looseness in the bearing fit of nozzle 12', due to initial clearance or subsequent wear, will cause a greatly magnified amount of misalignment of the nozzle at its discharge end, where accurate centering is important. In my improved construction, however, the misalignment of the delivery end of the nozzle is limited to the actual amount of play permitted by the clearance in the bearing at the delivery end.

My improved form of construction also permits the elimination of packing between the nozzle and its bearings, as any steam leading from the steam chamber past the main bearing surface of the nozzle cannot escape into the water chamber as in prior constructions, but is confined in the annular space between the nozzle and web, from which it can escape only through the bearing surface at the outer end of the nozzle. Any steam passing through the bearing surfaces is delivered in the direction of the main steam jet at a point within the water cone and will in no way diminish the efficiency of the injector.

It is particularly to be noted that the extended web portion of sleeve 23 is spaced, except at the bearing end, from the nozzle 12, in all positions of the latter. This will be clear from an inspection of Fig. 2 which shows the nozzle in both extreme positions. This construction forms a closed annular chamber between the web and nozzle, which serves as an insulating chamber between the water chamber 10 and the interior steam space of nozzle 12. Referring again to Fig. 3, it will be apparent that a certain heating effect, 105 detrimental to the operation of the injector, will be caused by the conduction of heat from the steam passing through the nozzle 12' through the walls thereof to the water in the chamber 10', and it will be equally apparent that the amount of heat transmitted from the steam jet within the nozzle to the water in the surrounding water chamber will be materially reduced by the closed chamber with which my improved construction surrounds the nozzle.

It may be further pointed out that the improved form of nozzle embodying my invention may be readily applied to existing injectors by fitting a web-carrying sleeve 120

thereto with a nozzle suitably fitted in the sleeve, or by increasing the bore of the passageway through the injector housing to accommodate the addition of a sleeve between the housing and a nozzle of standard outside diameter.

What I claim is:

1. In an injector, a housing, a cylindrical bearing located in said housing, a water cone mounted in said housing and spaced from said bearing to form a water chamber, a steam nozzle slidably mounted in said bearing, said nozzle having an extension extending through said chamber into said cone, and a bearing located within said cone and slidably engaging said extension.

2. In an injector, a housing, a cylindrical bearing located in said housing, a water cone mounted in said housing and spaced from said bearing to form a water chamber, a steam nozzle slidably mounted in said bearing, said nozzle having an extension of reduced diameter extending through said chamber into said cone, a bearing located within said cone and slidably engaging said extension, and an annular web separating the portion of said nozzle between said bearings from said chamber.

3. In an injector, a water cone, a housing forming a water chamber communicating with said cone, a cylindrical bearing located in said housing, said bearing being spaced from and in alignment with said cone, an annular web extending from said bearing through said chamber and forming a cylindrical bearing within said cone, and a steam nozzle slidably mounted in said bearings, said nozzle and web being spaced to form a closed annular chamber between said bearings.

4. In an injector, a housing forming a steam chamber and a water chamber, a cylindrical bearing located between said chambers, a water cone mounted in said housing, an annular nozzle slidably mounted in said bearing and extending through said water chamber into said cone, and an annular web surrounding said nozzle between said bearing and said water cone whereby steam leakage through said bearing from said steam chamber into said water chamber is prevented.

5. In an injector, a housing forming a

steam chamber and a water chamber connected by a cylindrical passage, a sleeve fixedly mounted in said passage, said sleeve having an annular web extending through said water chamber, and a steam nozzle slidably mounted in said sleeve.

6. In an injector, a housing forming a steam chamber and a water chamber connected by a cylindrical passage, a water cone mounted in said housing in alignment with said passage, a cylindrical bearing-forming sleeve fixedly mounted in said passage, said sleeve having a conical web extending through said water chamber into said cone and forming a cylindrical bearing at its outer end, a steam nozzle having a cylindrical portion slidably mounted in said first named bearing and a conical portion terminating in a cylindrical end slidably engaging said last named bearing.

7. A nozzle assembly for injectors comprising a sleeve member having an inner surface forming a pair of spaced cylindrical bearings, and a nozzle mounted in said sleeve member and slidably engaging said bearings, said nozzle being spaced from said sleeve member intermediate said bearing to form a closed annular chamber.

8. A nozzle assembly for injectors comprising a sleeve member having a cylindrical portion forming inner and outer cylindrical bearing surfaces and a conical web portion forming at its outer end an internal cylindrical bearing surface of reduced diameter in alignment with said first named bearing surfaces, and a nozzle located in said sleeve member, said nozzle comprising a pair of spaced cylindrical surfaces slidably engaging the internal bearing surfaces of said sleeve member and an intermediate portion spaced from said sleeve member.

9. A nozzle assembly for injectors comprising a sleeve member forming a pair of spaced cylindrical bearings and having an opening passing through one of said bearings, and a steam nozzle located in said sleeve and slidably engaging said bearings, said nozzle having a recess therein registering with said opening in a plurality of positions of the nozzle.
